TIMING APPARATUS

Filed Oct. 29, 1928

UNITED STATES PATENT OFFICE

RAYMOND M. HICKS, OF EAST ORANGE, NEW JERSEY

TIMING APPARATUS

Application filed October 29, 1928. Serial No. 315,720.

This invention relates to timing apparatus and more particularly to electrical circuits and apparatus for giving visual or other signals to numerous operatives at predetermined intervals.

Although not limited thereto, the invention is particularly adaptable for use in connection with the method of timing the use of electrical circuits such as telephone lines, as described and claimed in the patent to Jesse L. Boynton, No. 1,664,873, issued April 3, 1928.

The objects of the invention include the provision of apparatus of the type indicated, which is dependable in operation and relatively simple in construction.

Further and more specific objects, features and advantages will more clearly appear from the detailed description given below, taken in connection with the accompanying drawing, which forms a part of this specification.

The drawing schematically illustrates circuit arrangements and accompanying devices as comprising one embodiment of my invention.

In the drawing an incandescent lamp is indicated at 10 which may be of any suitable type such as is used as indicating lamps on telephone central office switchboards. One of such lamps may be located at each of numerous operatives' positions on the switchboard. One terminal of each of such lamps may be connected to battery and ground as indicated at 11, and the other terminal 12 may be connected to one of a plurality of lead wires as at 13. For example, if the switchboard is provided with 72 positions, 12 of the lead wires 13 may be provided, each lead wire running to 6 of the lamps connected in parallel. The manner in which the lamps for the various successive positions along the switchboard may be connected with the various wires 13, is indicated in the drawing. For example, the lower wire is indicated as being connected to "positions" 1, 4, 7, 10, 13 and 16. Accordingly, when a ground connection is applied to this wire, the lamps 10 at these

positions will be flashed for giving a signal to the operators at such positions. The circuits hereinafter described are so arranged that the wires 13 are divided into three groups, each group being energized successively, with the result that the signal lamp at each position is flashed at regular arbitrary predetermined intervals, but the signal lamps at adjacent positions on the switchboard are arranged to be flashed at different times. For instance, when the lamp at position 4 is flashed, the lamps at positions 3 and 5 will not be flashed, but at a predetermined time after the flashing of the lamp at position 4, the lamp at position 5 will be flashed and at a later interval the lamps at positions 3 and 6 will be flashed. Accordingly, when a signal is given to a certain operator, indicating that certain steps must be taken to control overtime payments, for example, on the telephone lines under her control, she may readily attend to such duties and if an excess number of telephone calls should occur at her position at that time, the operators at the adjacent positions will be free to assist in making connections for such excess calls, inasmuch as such adjacent operators will not be required at that particular moment to take steps to collect overtime payments.

The three groups of wires 13 respectively are under the control of relays as at 14, 15 and 16, each of such relays having four "make" contacts as at 17, connecting the corresponding four lead wires 13 to a ground as at 18 when one of said relays is energized. Each of the relays therefore controls the energization of four of the connection wires 13, which in turn control the flashing of 24 lamps arranged at the various operators' positions in the manner indicated in the drawing, the current to the circuits of these 24 lamps being divided between four of the contacts 17 in order to minimize deterioration of the contacts.

One terminal of each of the relays 14, 15 and 16 may be connected to battery and ground as at 19, the other terminals respectively running to cam operated switches as at 20, 21 and 22 arranged to operate the

5 relays successively according to a predetermined cycle of operation. From the switches 20, 21 and 22, circuits are continued by a connection wire as at 23 to another cam operated switch as at 24, thence by a connection wire 25 to a pair of "make" contacts as at 26 on a relay 27, thence to ground 28. The relay 27 may be connected as indicated to a "busy back flashing circuit" or other 10 suitable source of current which is intermittently supplied at a suitable frequency to give the desired flashing effect at the lamps 10. A pair of contacts is provided at 26 in order to insure dependability of operation. 15 It will be observed that the function of the relay 27 is to intermittently apply the ground connection 28 to the circuit of connection wires 23 and 25, thereby operating relays 14, 15 and 16 according to time intervals depending upon the manner of operation of the cam operated switches 20, 21, 22 and 24.

20 The cam operated switches 20, 21, 22 and 24 respectively may be controlled by cam members 29, 30, 31 and 32. Cam member 32 may be mounted to rotate with a shaft 33 to which in turn rotational movement may be intermittently imparted as by a magnet 34 operatively associated with the shaft as by a pawl and armature member 35 and ratchet 36. The circuit of magnet 34 25 may be intermittently energized at intervals to impart the desired speed of rotation to the shaft 33. For example, the magnet 34 may be connected in the usual electric clock circuit so as to receive one impulse during every six seconds. The ratchet 36 may for example be provided with ten teeth, in which event the cam 32 will revolve at the 30 rate of one revolution per minute.

40 A gear box as at 37 may be associated with the shaft 33 for driving a shaft 38 carrying the cams 29, 30 and 31. The gear ratio may be such for example as to cause 45 shaft 38 and the cams carried thereon to revolve at the rate of one-tenth revolution per minute.

50 The cam 32 may be provided with a raised portion 39 for engaging the switch 24 to close the same during substantially one-third of the time of each revolution of the cam 32. Each of the cams 29, 30 and 31 may be provided with a pair of raised portions as at 40 for engaging the corresponding 55 cam switches to cause the same to close twice during each revolution of said cams, the closing period in each case being, for example, approximately one-twentieth of the period of one revolution. The raised portions 40 on the several cams are placed 60 in angular positions such that during the first 20 second interval of each of three succeeding minutes, the three relays 14, 15 and 16 respectively will operate to flash the corresponding groups of lamps for periods of

20 seconds. During the succeeding two minutes none of the lamps will be flashed. Thereafter the cycle of operation may be repeated so that each of the signal lamps on the switchboard is caused to flash for a period of 20 seconds once during every five minutes. The raised portion 39 on the cam 32 is placed at an angular position, such that the switch 20 makes contact before switch 24 closes, and also so that switch 20 moves to open position only after switch 24 has broken the circuit. Switches 21 and 22 are also preferably arranged to cooperate with switch 24 in like manner so that the operating circuit of relays 14, 15 and 16 may be finally "made" or "broken" by the relatively rapidly operating switch 24, the relatively slowly operating switches 20, 21 and 22 actuating only when their circuits are deenergized. It may be noted that switch 24 at times may operate when the relay 27 is deenergized, so that breaking of the circuit will not always occur at the contacts of switch 24 when the same operates. The life of the contacts of switch 24 is thereby considerably prolonged.

55 It will be observed that with the above described arrangement, the operating current necessary for the numerous lamps is distributed among numerous contacts, whereby the possibility for deterioration of the contacts is materially reduced. Furthermore, while the relatively slow moving contacts for controlling the lamp relays are necessarily operated according to a predetermined time relationship, the possibility of arcing at such contacts is eliminated by reason of the control effected by the relatively rapidly moving cam operated switch and the flashing relay. The circuits and devices are therefore arranged to provide dependable operation over a relatively long period of years.

60 While the invention has been described in detail with respect to a preferred embodiment of the same, it will be understood by those skilled in the art, after understanding the invention, that various changes and modifications may be made without departing from the spirit and scope of the invention, and it is intended therefore in the appended claims to cover all such changes and modifications.

65 What is claimed as new and desired to be secured by Letters Patent of the United States is:

70 1. A lamp flashing circuit arrangement comprising several contact devices respectively for preparing circuits for controlling several groups of lamps successively, and an additional and relatively more rapidly moving contact device for establishing a current in a circuit running to said first named contact devices after any one of the latter has moved to circuit closing position,

and for breaking such current before the latter moves to open circuit position.

5 2. A lamp flashing circuit arrangement comprising several contact devices respectively for preparing circuits for controlling several groups of lamps successively, and an additional and relatively more rapidly moving contact device for establishing a current in a circuit running to any one of said first named contact devices, and for 10 breaking such current before the latter moves to open circuit position.

15 3. In apparatus of the class described, a plurality of groups of electrical signaling devices, said groups being divided into subgroups, a multicontact relay controlling operating circuits for each of said groups and having a contact individual to each subgroup, rotatable contact devices respectively 20 for preparing circuits for controlling said relays, and an additional and relatively more rapidly moving contact device for establishing a current in a circuit running to any one of said first named contact devices and 25 for breaking such current before the latter moves to open circuit position.

4. In apparatus of the class described for use in connection with a series of switchboard operators' positions, an indicator 30 lamp at each of said positions, means to flash said lamps in predetermined sequences, pluralities of the lamps respectively at separated positions being flashed concurrently, said means comprising a clock controlled 35 circuit, a rotatable element controlled thereby, a plurality of rotatable switch devices, means operatively connecting said rotating element to rotate said switch devices as a group at a rate slower than the rotation of 40 said element, a flashing circuit, and multicontact relay means operating under the control of said flashing circuit and through 45 said switch devices whereby each of said pluralities of lamps is flashed in succession once during each cycle of movement of said switch devices.

In testimony whereof I have signed my name to this specification.

RAYMOND M. HICKS.
